Letters Patent

The schedule referred to on this Letters Patent, and making part of the same, containing a description in the words of the said Joseph Claghorn Mandell and R. B. Ricketts shows class of their improvement in the machine for moulding clay into pipes, Pots, Jars, Jugs, cups and other kinds of Pottery -

To all to whom these Presents shall come:

Be it known, that the
Joseph Claghorn Mandell and Richon Baron Ricketts in the
county of Mason and state of Kentucky, have invented a new and
useful machine for moulding of clay into Pipes, Pots, Jars, Jugs
cups and other kinds of Pottery, and that the following is a full
and exact description thereof. The Model is made to a scale
of one inch to a foot as may be wanted in a vertical inverted, hori-
zontal or other mode, and worked by physical or other force. Fig. 1
in this drawing represents the machine supported by the frame with the
rolling and casting power - A. B. are slider boxes supporting
and guiding a spindle M. on spindle M. is a fly wheel 2 which gives
motion and power to spindle M. and on the lower end is a punch
P. screwed on to the spindle M. with a steel collar or ring, which
cuts off the surplus clay by being forced on the top of the moulds H.
H. is the handle started by a wheel of the hand and moves a spindle
M. flywheel 2 and punch P. On spindle M. is two collars or rings
forked in the poly between, to hold up and to press down spindle
M. M. is keyed or fixed on the top of P.P. from which extends said
forked iron P.P. above pass down through the frame and are con-
nected to P.P. below the joints, and P.P. is fastened to lever tricelle
T. at the bottom by rolling joints, lever tricelle T. is fastened at the
near end by a joint to the frame and from the front part of the tricelle
lever T. extends a cord or strap up and on to pulley 3. which is on

a snaking roller shaft with two other pulleys on the same shaft from the rear pulley winds a cord or strap down and fastened to spring D winding inversely to the one on pulley J. The cord or strap is wound on to the pulley J by the spring D and from the rear pulley by the same spring D, lifting up lever bracket E. The third cord or strap extends from the middle pulley on said snaking roller shaft, down and under pulley I, up and out to a double pulley on spindle J, and from said double pulley extends the fourth cord or strap down and made fast to spring H, inversely to the third cord or strap on said double pulley on spindle J. The lower or left end of spindle J furnishes the hole for the pipe stem on which there is a steel collar or ring to cut off the surplus clay at the other end of spindle J as a groove for a forked lever I to fit in, which holds spindle J while in its action and rotation, forked lever I is forced into snaking roller H, which is supported by two moveable brackets and screws A. B. C. D. E. F. G. H. I. J. K. L. M. L. is a lever framed into snaking roller H. J. and G. are fastened into roller H. with keys so as to be immovable. L. is fastened to lever G at the top by a screw forming a joint and at the lower end to P. on the left by a pin forming a joint, — K. K. are two screws supporting P. on which are two keys and levers for guiding and supporting spindle J. B. B. are the clamps on which the moulds H. are fastened with screws L. L. The rear clamp B. is fastened with a hinge to the frame at the lower end and opened with a spring on the left side. The front clamp B. is fastened at the top and bottom to the frame lever O is fastened to the frame on the right, and on the left to lever E forming joints at both ends. Lever E is fastened by a joint to the frame on the rear. The moulds H. are closed and wedged together by pressing down lever E which wedges Lever O between a block, and the rear clamp B. and by lifting up lever E. the moulds are opened by the spring above mentioned. For moulding pots, jugs, jugs cups and other kinds of pottery, the spindle J. is not wanted, and may be taken off by taking out a pin where J. is connected to P. and the cord or strap off of the middle pulley, the moulds H. may be taken

off and the punch A, by unscrewing them, and others put on if required. Nails may be substituted for the springs -

Fig. 2. 39 1/4. In the drawing represents the small model which shows the moulds and punch for moulding pots, cups and other kinds of smooth pottery. Fig. 3 is a punch for fig. 1, the punch has a projecting square and a cross hole on the top, marked A, for screwing on and off of the spindle. It is a vent hole which may be larger or greater if required for discharging the surplus clay at the hole B on the top -

Fig. 4 is a specimen of one half of the mould, the dotted lines D D shows the outer edges sloped or bevelled off leaving the inner edges to close on each other and readily forcing the surplus clay, should any fall between them when closing, also requiring but little or no trimming. Fig. 5 is the inside view of the one half of the moulds. C C are the stay pins or holes, the tops of these moulds project inwardly the thickness of the pot, cup or other vessel, preventing the moulding from being drawn out of the moulds with the punch - Fig. 5. 6. 7. 8. Represents a jug moulded, and the bottom cutter punch and moulds - Fig. 5. represents a jug moulded ready for receiving the bottom C, which is to be forced into the shoulders (see dotted line) when in order for finishing - Fig. 6 represents a cutter in shape of a Tay-lor's thumb for cutting the bottoms (see fig. 5) the clay is rolled to a proper thickness with a rolling pin commonly used by Potters - Fig. 7. Represents the punch the head of which sinks into the moulds below the inward projection of the top which projection is about half the thickness of the jug and forms a shoulder for the bottom (see dotted lines in fig. 5. 7. 8) also vent holes C. & D. somewhat and square A in fig 2 -

Fig. 8 represents the one half of a mould differing in shape from the inward projection of the top from fig. 3. 3. 4, which projection is about equal to one half the thickness of the sides of the jug - What we claim as our own invention and not previously known is the projection of the machine frame with the acting and working powers, produced by lever, brace, puzzle, wedge, wheel, roller

shafts, cords or straps, springs or weights, also the moulds and apparatus represented in the figures 2, 3, 8 to also 5, 6, 7, 8 and in the above specification and drawings. We also claim the improvement of the pipe moulds, by attaching steel collars or rings on the top and side, and by sloping or beveling off the outer edges, leaving the inner edges to close on each other, of which forces the surplus clay that falls between them, when closing and requires but little or no trimming to the Pipes.
